KITE CONTROL

Kenneth C. Howard, Fort Worth, Tex.

Application June 16, 1950, Serial No. 168,552

3 Claims. (Cl. 244—153)

1

This invention relates to kites, and has reference to a kite control for changing the plane of the kite relative to the length of the kite string.

An object of the invention is to increase the maneuverability of the kite and thereby create greater interest in flying the same.

A feature of the invention is to provide a rotatable control lever between the kite's bridle and the main string and whereby the operator may change the relative center of lift with respect to the kite's surface, and thereby cause the kite to climb, dive, or fly to one side or the other.

The invention will be more readily understood by reference to the accompanying drawings and the following description.

Figure 1 is a perspective view of a kite, and showing one form of the present control installed between the bridle and the main string. The control is shown proportionately larger than the area of the kite to illustrate the invention to a better advantage.

Figure 2 is an enlarged perspective view of the control illustrated in Figure 1.

Figure 3 is an enlarged side elevation of Figure 2.

Figure 4 is a front elevation of a modified form of the invention, and

Figure 5 is a perspective view of the control arm of the form of the invention illustrated in Figure 4.

The form of the invention illustrated in Figures 1 through 3 includes an annular plate 10 having forwardly directed teeth 11 therearound. A shaft 12 having a head 13 on one end is rotatably positioned through the center of the plate 10. The end of the shaft 12, opposite its head 13, is longitudinally slotted, as at 14, to pivotally receive a lateral control arm 15. The pivotal connection last referred to is carried out by means of a pin 16 positioned and secured in opposite sides of the end of the shaft 12 and through the control arm 14 intermediate the latter's ends. One end of the control arm 14 has an integral forwardly directed projection 17 having a hole 18 through which one end of the main kite string 19 is tied. An arcuate spring 20 is riveted or otherwise secured on the shaft 12 near the plate 10, and is outwardly directed to bear against the end of the control arm 14 opposite the projection 17. The action of the spring 20 moves the end of the arm 14 including the string attachment hole 18 towards the teeth 11.

Beneath the string attachment hole 18 and adjacent the teeth 11, there is an elongated opening 21 in and parallel with the length of the arm 15.

2

A flat ratchet pawl 22 is bent at one end, as at 23, where it is received through and is pivotally mounted in the slot 21 where it is arranged to contact the teeth 11, as shown in Figures 2 and 3.

5 A curved leaf spring 24 is attached at one end, as by riveting, to one side of the arm projection 17 and is arranged to bear against the outer surface of the pawl 22. A washer 25 is positioned around the shaft 12 and against the face of the plate 10 opposite the shaft head 13, and which washer is held in place by means of a cotter key 26 positioned through the shaft 12. Holes 27 are formed through the edge of the plate 10 to receive and secure the forward ends of the bridle strings 15 28 of the kite 29. As in conventional kites, the bridle strings 28 converge toward a point forwardly of the kite surface 30 which is the relative center of lift, and the point at which the main string 19 is ordinarily attached. As will 20 become apparent, the referred to relative center of lift may be varied 360 degrees for changing the altitude or angle of the kite surface 30 relative to the length of the main string 19.

The form of the invention illustrated in Figures 4 and 5 embodies substantially the same mechanical features as the foregoing. There is an annular plate 31 having raised but inwardly directed ratchet teeth 32 around on its forward surface. The control arm 33 is journaled on the shaft 34 which projects forwardly from the center of the plate 31. A V-shaped spring 35 is secured on one of its sides to one end of the control arm 33 and the remaining end of said spring is arranged to contact and bear against corresponding sides of the ratchet teeth 32. There is a ratchet arm or pawl 36 also journaled on the shaft 34 and positioned between the control arm 33 and the face of the plate 31. The outer end of the pawl 36 is also provided with a V-shaped spring 35, as described, and is also arranged to engage the ratchet teeth 32 in the same manner as the first described V-shaped spring 35.

The end of the control arm 33 opposite its attached V-shaped spring 35 may be provided with 45 an offset integral extension 37 for sliding contact with the surface of the plate 31. A coiled compression spring 38 is positioned around the shaft 34 and has its ends connected with the control arm 33 and the pawl 36 for normally spreading 50 the last named parts apart. An eyelet 39 on the control arm 33 slidably receives the main kite string 19, the end of which is tied in an opening 40 in the outer end of the pawl 36. Holes 41 are formed in the edge of the plate 31 55 to receive and secure the bridle strings 28.

The manner of operating both described forms of the invention is the same. The kite is first flown with the control arm 14 or 33 in its raised vertical position, so as to tilt the kite plane 30 forwardly and thereby increase the lift. After the kite is in the air the weight of the string 19 causes the same to sag and increase the forwardly tilted attitude of the kite plane 30, and in which event it becomes desirable to lower the relative point of string attachment to the bridle strings 28. This may be done by rapidly and repeatedly slackening the string 19. In the first described form of the invention the resulting tilting movement of the control arm 14, and the action of the pawl 22 on the teeth 11, causes the arm to progressively rotate around the plate 10. Thus, any desired rotated position of the arm 14 may be attained for making the kite 29 climb, dive, or fly to the right or left.

Similarly, the rotation of the control arm 33 of the last described form of the invention will attain the same results. By slackening the string 19, the arm 33 and the pawl 36 are spread apart by action of the coil spring 38 and by reason of the engagement of the V-shaped springs 35 with the ratchet teeth 32. As the string 19 becomes taut, the arm 33 and pawl 36 are brought together. Thus, by repeatedly slackening the string 19, the control arm 33 may be changed to any desired rotated position.

The present invention is not limited to the construction herein shown and described, but may be made in many ways within the scope of the appended claims.

What is claimed is:

1. A kite control to be mounted between the string and the bridle of a kite, said control comprising: an annular plate having teeth circumferentially projecting therefrom, a connecting arm positioned substantially parallel with respect to the plane of said plate and rotatably mounted within the axial center of said teeth, means connecting said kite string with said arm outwardly of said axial center of said teeth, and a spring actuated ratchet connected with said arm and adapted to engage said teeth for carrying out the referred to rotatable movement of said arm.

2. A kite control to be mounted between the string and the bridle of a kite, said control comprising: an annular plate having teeth therearound and projecting from one surface thereof, a shaft rotatably mounted in the axial center of said plate and projecting therefrom in the same direction as said teeth, a longitudinal slot in said projecting end of said shaft, a control arm pivotally mounted in said slot and having one end thereof positioned adjacent said teeth, a pawl pivotally connected with said arm and arranged to contact said teeth, a spring mounted on said arm and in contact with said pawl and arranged to move the latter toward said teeth, a spring mounted on said shaft and in contact with said arm and also arranged to move said pawl toward said teeth, and means connecting said string with said arm adjacent said pawl.

3. A kite control to be mounted between the string and the bridle of a kite, said control comprising: an annular plate having inwardly directed ratchet teeth around one face thereof, a shaft projecting from the axial center of said plate and face thereof including said ratchet teeth, a control arm rotatably mounted on said shaft and having one end thereof disposed toward said teeth, a spring carried by said control arm and arranged to contact said teeth, a ratchet arm also rotatably mounted on said shaft between said plate and said arm, a spring carried by said pawl and arranged to contact said teeth, a compression spring connecting said arm and said pawl, means carried by the outer end of said arm to slidably receive said kite string, and means connecting the end of said string with said pawl.
